UNITED STATES PATENT OFFICE.

JAMES G. G. ROSS, OF NEW YORK, N. Y., ASSIGNOR TO NICHOLAS POWER COMPANY, OF NEW YORK, N. Y., A CORPORATION OF NEW YORK.

FILM-GUIDING DEVICE.

1,210,212.

Specification of Letters Patent. Patented Dec. 26, 1916.

Application filed November 16, 1912. Serial No. 731,684.

To all whom it may concern:

Be it known that I, JAMES G. G. Ross, a citizen of the United States, residing at the city of Greater New York, county of Richmond, and State of New York, have invented new and useful Improvements in Film-Guiding Devices, of which the following is a specification.

This invention relates to a film guiding device for motion picture projecting machines and has for its object to provide a film guide for the edge of the film which will not be injured by the friction produced by the rapidly moving film and which will not adhere to the film or otherwise damage it.

In moving picture projecting machines as at present constructed the films are placed in the form of a reel in a fire-proof magazine forming part of the machine, and from this magazine the end of a film is fed through a suitable guiding device, called in the trade a "magazine valve," thence through a film feeding device past the projection aperture and through a similar magazine valve into the receiving magazine supported on the lower part of the machine. It has been found in practice that the edge of a film moving rapidly in contact with the brass forming the edge of the valve wears the same so that in a little while it presents a jagged surface, which, unless at once repaired or replaced seriously damages the edge of the film.

A valve of this type and the manner of attaching it to the film magazines, is shown in the patent to Nicholas Power No. 959,601 granted May 31, 1910. The valve shown in the drawings of this application is somewhat modified in configuration but is mounted in the magazine in the same way with its upper rollers within the magazine and its lower rollers below the same.

My present invention entirely obviates this difficulty and is so designed that it may be applied to the magazine valves now in use without modification or removing them from the machine.

In the accompanying drawing I have illustrated my improved film guide as attached to a magazine valve of the design now in common use, and in said drawings Figure 1 shows a valve detached from the magazine and with my improved guide attachment thereon; Fig. 2 is a transverse

vertical section through the median line of the valve shown in Fig. 1 and Fig. 3 is a perspective view of my improved attachment separate from the valve.

Referring now to the drawings in which like reference characters indicate like parts throughout the several views, 1 indicates the brass body of the magazine here shown as comprising two similar side portions connected at one edge by an integral web 2. 65 The body 1 comprising upwardly extending brackets in which are mounted rollers 3 for guiding the film as it passes into the valve and downwardly extending brackets in which are mounted similar rollers 4 for 70 guiding the same as the film passes out of the valve. The edge of the frame 1 opposite the web 2 is left open between the rollers so that the film can be slipped edgewise into the valve when the reel is placed in the 75 magazine. One of the rollers 3 is mounted in inclined slots as shown in Fig. 1, the purpose of which is to cause the roller to press against the film so that in case the film catches fire during its movement from 80 one reel to the other, the rollers will extinguish the flame by reason of their chilling effect, thereby preventing the flame reaching the reel of the film in the magazine and causing a serious conflagration. 85

The body 1 of the valve is provided with integral flanges beyond the roller supporting brackets providing a suitable supporting surface when the valve is attached to the magazine in the manner indicated in Fig. 1. 90 The space between the base and each of the rollers 3 is closed by suitable metal plates 4 as indicated in Figs. 1 and 2 to form a narrow chute for extinguishing the flame in the manner described in the above-mentioned 95 prior patent should the flame succeed in passing the rollers.

The rollers 3 are slightly enlarged at each end so as to engage the film at the margins and thereby avoid scratching the emulsion 100 surface. It will however be understood that the space between the main portion of the rollers is sufficiently constricted to prevent the passage of the flame.

In ordinary operation the edge of the film 105 is guided by the inner face of the web 2 to maintain the film in proper alignment with the feed rollers. It has been found by long experience that the edge of the film cuts into the brass of the web 2 to an extent sufficient 110

to form a groove therein, in a comparatively short time. This groove, while not damaging the valve to an extent to seriously weaken the same, necessitates the immediate 5 replacement of a valve for the reason that the roughened surface of the brass causes the film to wear on the edge and also not infrequently splinters in the surface catch the film and so hinder its feeding that the 10 feed sprockets tear out the margin of the film beyond the holes in which they engage, sometimes entirely ruining a large portion of the film. To obviate this difficulty I provide a supplemental guiding attachment for 15 the magazine valve which keeps the edge of the film out of contact with the brass. This guiding attachment is shown detached in Fig. 3 and comprises a frame piece 5 in which is supported a small piece of glass 6, the glass being held in place by the ends 5' of the piece 5 which are bent over the ends of the glass to form suitable ways therefor. The edges of the piece 5 below the glass 6 are bent over in a similar manner at 5" to fit 20 the edges of the web 2 as shown in Fig. 1. The glass 6 is thicker than the metal of the web 2 and consequently its face projects beyond the face of the web so that the edge of the film is guided by the glass and held 25 out of contact with the web. I have found by experiment that the smooth surface of the glass affords much less frictional resistance to the passage of the film than the brass surface so that there is much less wear on 30 the edge of the film, and furthermore, the glass being a great deal harder is not cut or roughened by the film and preserves its smooth glazed surface throughout the ordinary life of a projecting machine.

35 40 I have shown my improved attachment as applied to only one edge of a magazine valve, but it will be understood that it may be applied at both edges if desired, particularly if the valve is closed at both edges, as 45 is sometimes the case.

I have designed my improved guide piece as a separate piece from the magazine valve

so that it may be readily attached to valves in machines now in use without modification of the valve or detaching the same from 50 the machine, but it will of course be understood that if desired the holder for the glass piece 6 may be formed integral with the structure of the valve or attached thereto in any suitable manner. 55

Having thus described my invention, what I claim and desire to secure by Letters Patent is:—

1. In a motion picture projecting machine, the combination with a film-guide member having a passage way for the film, of means for engaging the edge of the film and holding it out of contact with the end of said passage way. 60

2. In a moving picture projecting machine the combination of a member having a film guide-way closed at one end, and means comprising a member having a glazed wearing surface for engaging the edge of a film and holding it out of contact with the 70 end of said guide-way.

3. An attachment for film-guides, comprising a member having a glazed wearing surface and means for attaching the same to the guide-way in such manner that its 75 glazed surface projects beyond the surface of the end wall of the guide-way.

4. An attachment for magazine valves having an end wall with oppositely projecting edges comprising a supporting member 80 having ways for detachably engaging the projecting edges of the valve, and a piece of glass carried by said member above said ways and having its face projecting beyond the surface of said valve adjacent the path 85 of the film.

In witness whereof I have hereunto set my hand at the city, county and State of New York, this 11th day of November, 1912.

JAMES G. G. ROSS.
